UNITED STATES PATENT OFFICE.

GEORGE M. HARSH, OF BALTIMORE, MARYLAND.

DESIGN FOR A TABLET OF CHEWING-GUM.

SPECIFICATION forming part of Design No. 23,096, dated March 6, 1894.

Application filed January 27, 1894. Serial No. 498,255. Term of patent 14 years.

To all whom it may concern:

Be it known that I, GEORGE M. HARSH, a citizen of the United States, residing at Baltimore, in the State of Maryland, have invented and produced a new and original Design for a Tablet of Chewing-Gum, of which the following is a specification.

The drawing shows a perspective side view of a tablet of chewing gum.

- The design consists of a circular disk or tablet, *a*, having a diametrical ridge or bead, *b*, extending across one side and dividing the

surface of said side into two equal parts; the surface of the reverse side is plain.

I claim—

The design for a tablet of chewing gum herein shown and described.

In testimony whereof I affix my signature in the presence of two witnesses.

GEORGE M. HARSH.
